IGNITION MECHANISM FOR INTERNAL COMBUSTION ENGINES

Walter J. Spengler, Sidney, N. Y., assignor, by mesne assignments, to Bendix Aviation Corporation, South Bend, Ind., a corporation of Delaware

Application June 10, 1931, Serial No. 543,343

15 Claims. (Cl. 123—148)

This invention relates to ignition mechanism for internal combustion engines and more particularly to breaker and distributor apparatus for battery ignition systems.

5 It is an object of the present invention to provide a new and improved breaker and distributor mechanism particularly adapted for battery ignition systems of multi-cylinder internal combustion engines.

10 Another object of the invention is to provide such a device embodying a dual breaker-distributor mechanism for use in twin ignition systems.

15 Another object is to provide such a device in which the breaker mechanism and the distributor mechanism are operated from a unitary driving element, and the various coil, breaker and distributor units are each readily removable and replaceable without disturbing any of the other elements of the mechanism.

20 A further object is to provide such a device in which each element is readily accessible, and the moving parts including particularly the make and break mechanism are arranged so that they can be exposed for observation and/or adjustment during the normal operation of the device.

25 Another object is to provide such a device embodying provisions whereby the same may be readily and quickly adapted for either clock-wise or counter clock-wise rotation.

30 Another object is to provide such a device having novel means for assuring proper lubrication of the moving parts over long periods of use.

35 A still further object is to provide such an arrangement which is compact and efficient, making possible the use of comparatively small blocks of insulating material for the high tension electrodes.

40 Another object is to provide such a device in which the various units are so constructed that the high tension circuits may be readily shielded to prevent radiation therefrom.

45 A further object is to provide such a device in which the arrangement of the units is such that the distributor mechanism may be removed and the make and break mechanism operated independently thereof and used as a replacement unit in installations provided with separate distributors.

50 Further objects and advantages will become apparent to those skilled in this art from the following description taken in connection with the accompanying drawings in which:

55 Fig. 1 is a side elevation, partly in vertical sec-

tion, of a preferred form of the invention showing the parts in assembled relation;

Fig. 2 is a perspective view of the device with one of the coil units partially disassembled;

Fig. 3 is a perspective view of the device taken 5 at a different angle from Fig. 2 and showing the various units further disassembled;

Fig. 4 is a plan view of the receptacle for the breaker mechanism;

Fig. 5 is a plan view of the breaker mechanism; 10

Fig. 6 is a section of the breaker mechanism and the receptacle therefor taken substantially on the lines 6—6 of Figs. 4 and 5;

Fig. 7 is a similar section taken substantially 15 on the lines 7—7 of Figs. 4 and 5;

Fig. 8 is a perspective view of an oil guard for the breaker mechanism;

Fig. 9 is a perspective view of the distributor mechanism showing its relation to the output electrodes; 20

Fig. 10 is a diagrammatic representation of the distributor mechanism and output electrode units in connection with a circuit diagram of the ignition system;

Fig. 11 is a perspective view of a portion of the 25 device partially disassembled showing a preferred method of shielding the output terminal block and conductors;

Fig. 12 is a detail of the same partly in section showing the parts in assembled position; 30

Fig. 13 is an elevation partly in section on a somewhat reduced scale of the device with the distributor mechanism removed to form a replacement unit for the breaker mechanism in dual ignition systems; and 35

Fig. 14 is an inverted plan view of the structure shown in Fig. 11 with the mounting flange removed.

Referring first to Figs. 1, 2 and 3 of the drawings, it will be noted that the device comprises 40 a hollow or skeleton frame 1 of generally rectangular shape having a pair of caps 2 and 3 mounted on two opposite sides thereof, a pair of terminal insulator blocks 4 and 6 (Fig. 10) on the other two opposite sides thereof, a breaker 45 mechanism 7 adjustably mounted in the top thereof, and a rotor shaft 8 journaled axially therein. The frame 1 is provided on its bottom with a flange 9 whereby the device may be suitably mounted on the frame of the engine, not 50 shown, and the rotor shaft 8 is provided with connecting means such as key 11 and nut 12 for attaching suitable coupling means thereto whereby the shaft may be driven from a rotating part 55 of the engine in proper timed relation therewith.

The caps 2 and 3 are located on the frame 1 by means such as dowels 5 (Fig. 2) and are suitably fixed thereto as by screws 10. These caps form receptacles for high tension generating means in the form of transformer coils 13 and 14 which are mounted therein in a unitary manner. Since these coils are of identical construction and are similarly connected in the ignition circuits of the engine, a description of one thereof will be sufficient. Each transformer comprises a laminated magnetic core 16 rigidly mounted in its cap as by means of screws 17 (Fig. 3), the magnetic circuit thereof being substantially completed by a U-shaped magnetic member 18 also rigidly mounted in the cap as by means of screws 19. The usual primary and secondary transformer coils are mounted on the core 16, one terminal of the primary coil being connected as indicated at 21 (Fig. 1) to a conducting strip 22 which is connected through a resistance 23 to the input terminal 20. The opposite end of said primary coil is connected as indicated at 24 to a conducting strip 25 which is connected at one end to a condenser 26 and at its other end to a conducting strip 27 having a flat contact portion 28 forming a coil terminal which extends within the frame 1 when the cap is mounted in its normal position thereon as indicated in Fig. 1. A bolt 29 is provided for holding the strips 22 and 25 in proper relation with the end plates 31 and 32 of the transformer coils, said bolt being suitably insulated from the strips as indicated at 33 and 34. The opposite terminal of the condenser 26 is grounded to the frame of the coil as indicated at 35. The inner terminal of the secondary of the transformer is, as usual, connected to the outer terminal of the primary coil, and the outer terminal of the secondary is connected to a high tension terminal member 36 which extends within the frame 1 when the coil unit is in assembled position thereon.

The upper end of frame 1 is provided with a partition 37 and a circular flange 38 forming a seat for the breaker mechanism 7. The partition 37 forms on its under side a seat for an anti-friction bearing 39 for the rotor shaft 8, and on its upper side is formed with a recess 41 adapted to be filled with absorbent material 42 held in place by suitable means such as a diaphragm 43, and adapted to be charged with lubricant as by means of an oil cup 44 (Fig. 6) connected thereto by a canal 45. The diaphragm 43 is preferably retained in place by peening over the edge of the opening 41 as indicated at 40. Openings 46 are formed in the partition 37 to allow the passage of the primary coil terminals 28 therethrough, whereby the upper surfaces of said terminals are substantially flush with the upper surface of said partition when the coil units are in assembled position.

The breaker mechanism 7 is mounted in a shallow cup 47 (Figs. 5 and 6) adapted to fit slidably within the flange 38 of frame 1 and normally retained therein with slight rotational freedom by suitable means such as a pair of posts 48 fixed in the partition 37 of the frame 1, extending through arcuate slots 49 in the bottom of the cup 47 and having yielding means such as springs 51 (Fig. 3) bearing on said cup and retained on the posts by collars 52 having a bayonet connection with the ends of said posts.

The breaker mechanism, which is in duplicate to cooperate with the two transformer coils, comprises a pair of breaker arms in the form of bell-crank levers 53 (Fig. 5) having contacts 54 at

one end normally urged into engagement with fixed contacts 55 by means such as springs 56 attached to the levers 53 as shown at 57, and to fixed anchorages 58 by means of screws 59. The other arms of the bell-crank levers are provided with cam followers 61 by which the levers are operated, the motion thereof being limited by adjustable stops 62 mounted on fixed posts 60. The anchorages 58 and posts 60 extend upwardly from a mounting plate 64 which is retained in the bottom of the cup 47 by suitable means such as screws 65. The bell-crank levers 53 are pivoted on posts 63 (Fig. 6) which are also mounted on plate 64 and are formed hollow for the reception of oil wicks 66. These wicks are arranged to contact at their lower ends with portions of the absorbent material 42 extending through arcuate openings 67 in the diaphragm 43 and are adapted to convey lubricant therefrom through openings 68 in said posts 63 to the bearing surfaces of said posts and breaker arms 53.

Contacts 55 are adjustably mounted on posts 69 extending upwardly from the plate 64 and suitably insulated therefrom as indicated at 71. Conducting strips 72 (Fig. 1) are arranged to connect the posts 69 with laminated spring brushes 73 adapted to make contact with the surfaces of the primary coil terminals 28 when the parts are in assembled position.

A cam 74 is rigidly mounted on the upper end of rotor shaft 8 by suitable means such as a key 70 (Fig. 9) and cap screw 75, and is arranged to operate the cam followers 61 whereby the breaker arms 53 are oscillated to open and close the contacts 54, 55. In order to provide lubrication for the bearing surfaces of the cam and cam followers, the cam is preferably provided with a longitudinal channel 80 (Fig. 1) containing an oil wick which at its lower end engages the absorbent material 42 in the oil reservoir 41 and at its upper end is arranged to be engaged by the cam followers. It will be understood that the breaker arms 53 are grounded through their pivots and by means of the spring members 56 whereby the contacts 55 are grounded except when lobes of the cam 74 are in engagement with the cam followers 61.

The lower end of the frame 1 is closed by a partition 76 preferably formed integral with the mounting flange 9, and forming on its upper side a seat for an anti-friction bearing 77 for the lower end of shaft 8. A distributor rotor in the form of a cylindrical block of insulating material 78 is rigidly mounted on the rotor shaft 8 in any suitable manner and is provided with a pair of conductors 79 and 81 having complementary arcuate portions or strips 82 and 83 and axially offset terminals 84 and 85. The arcuate strips 82 and 83 are slightly less than semi-circles and the offset terminals 84 and 85 are oppositely offset and are located at opposite sides of said rotor, as indicated most clearly in Figs. 1, 9, and 10. The rotor block 78 is so located on the shaft 8 that the arcuate strips 82 and 83 come opposite the high tension terminals 36 of the transformer coils 13 and 14, the terminals extending into close proximity to said strips when the parts are assembled whereby the high tension current from the coils is conducted to said strips. A pair of flanges 86 and 87 are preferably formed on said rotor 78 on opposite sides of the strips 82 and 83.

The terminal blocks 4 and 6 are of insulating material and have moulded therein sets of output electrodes 91, 92, 93, 94, 95, 96, 101, 102, 103, 104, 105, and 106 adapted to be connected by insulated

cables indicated collectively by numeral 97 to the spark plugs of the engine, not shown. The cables 97 are anchored in the terminal blocks by suitable means such as the pointed screws 98 which traverse the ends of the electrodes and pierce the cables. The device herein illustrated is adapted for a dual ignition system for a six-cylinder engine so that each terminal block 4 and 6 carries two sets of three electrodes, those in block 4 being numbered 91, 95, 93, and 106, 102, 104, and those in block 6 being numbered 96, 92, 94, and 101, 105, 103 respectively. When the blocks are assembled on the frame 1, the twelve electrodes become arranged in two coaxial circular series of six each, spaced sixty degrees apart, as illustrated in Figs. 9 and 10. The electrodes are adapted to be connected by the cables 97 to pairs of spark plugs in the engine cylinders, electrodes 91 and 101 being connected to cylinder No. 1, 92 and 102 to cylinder No. 2, etc. It will be noted that the correspondingly numbered electrodes in the two series, such as 91 and 101 are spaced 180 degrees apart so that they are simultaneously energized from the rotor terminals 84 and 85. In other words, referring particularly to Figs. 9 and 10, it will be seen that the rotor terminal 85 comes into operative relation with electrodes 96, 92, 94, 91, 95 and 93 in sequence, corresponding to a firing order of the engine of 6, 2, 4, 1, 5, 3 while the terminal 84 makes simultaneous connections with the corresponding series of electrodes 106, 102, 104, 101, 105, 103.

The terminal blocks 4 and 6 are held in assembled position preferably by a readily detachable connection such as the spring 108 (Fig. 2) having counter-sunk notched openings 109, 110 adapted to engage the grooved posts 111 and 112 and press the blocks against the frame 1 in an obvious manner.

The breaker mechanism is preferably inclosed by a readily detachable cap 113 which is maintained in position by means of spring clips 114 engaging with lugs 115 on the rim of the breaker cup, and may be provided with ventilator caps 116 as indicated. The breaker cup 47 is also provided with an arm 117 by which the cup may be rotated through angles permitted by the arcuate slots 49 in the base of the cup, in order to vary the timing of the breaker mechanism.

Referring now to Fig. 10 of the drawings which shows the circuit diagrams, it will be seen that the primary circuits comprise a battery 118 one terminal of which is grounded as indicated at 119 and the other terminal of which is connected by means of a manual switch 121 through leads 122, resistance elements 23 and connections 22 and 21 to the primary of transformer coils 13 and 14. The opposite terminals of the primary coils are connected through leads 24 and strips 25 to the condensers 26 and through the connections formed by strips 27, brushes 73, posts 69 etc. (Fig. 1) to the fixed contacts 55. When the cam followers 61 of the breaker arms 53 are not engaged by lobes of the cam 74, the movable contacts 54 engage the contacts 55 completing the primary circuits through ground connections formed by springs 56.

The breaking of the primary circuits by the opening of contacts 54, 55 by the cam 74 induces high tension currents in the secondaries of the transformers 13 and 14 which are conducted by the high tension terminal members 36 to the arcuate strips 82 and 83 of the rotor electrodes. As illustrated in Fig. 10, arcuate portion 83 is posi-

tioned to be energized from coil 14, and consequently the high tension current from said coil passes along said strip into the rotor terminal 85 and from thence through the electrode 96, which is opposite said terminal at this time, and 5 its corresponding cable to the spark plug of the cylinder No. 6 of the engine. The high tension current generated by the transformer 13 is simultaneously fed through the arcuate strip 82 to the rotor terminal 84 which is at this time in operative 10 relation with the output electrode 106 in the block 4, which is connected to a second spark plug of cylinder No. 6 of the engine.

From the foregoing description the operation of the device is obvious. Rotation of the shaft 8 15 by the engine at half engine speed causes the breaker arms 53 to be operated by the cam 74 so as to break the primary circuits and cause the generation of ignition currents in the proper timed relation to the operation of the engine in 20 the usual well-known manner. The rotor distributor picks up the high tension currents from the transformers 13 and 14 and transmits the same to the output electrodes in the sequence indicated. It will be seen that transformer 14 25 energizes electrodes 96, 92 and 94 by means of the rotor conductor 83, 85, and then energizes electrodes 101, 105 and 103 by means of the rotor conductor 82, 84, while simultaneously therewith the transformer 13 is energizing electrodes 106, 30 102, and 104 from the rotor conductors 82, 84 and thereafter electrodes 91, 95 and 93 from the rotor conductor 83, 85.

The device here illustrated is adapted for rotation in the direction of the arrow shown in 35 Figs. 5 and 9, but operation in the reverse direction may readily be secured by simply reversing the position of the breaker arms 53 and transposing the stop posts 60 and the contact posts 69 with its conductor strips 12. The 40 springs 56 will then be fixed to duplicate anchorages 124 (Fig. 5) provided for that purpose.

During operation, if excessive amounts of lubricant are applied to the cam surfaces, it may be found necessary to provide a lubricant guard 45 for the contacts 54, 55. A device for this purpose is illustrated in Figs. 5 and 8 wherein is shown a thimble 125 having a cylindrical portion 126 adapted to surround the cam 74, and having openings 127 to allow the cam followers 61 to engage the cam 74. The mounting flange 128 of this thimble is provided with duplicate openings 130 therein whereby it may be retained by the screws 129 in proper position to guard the contacts 54 and 55 in either direction of rotation of 55 the device.

By reference to Figs. 11 and 12, it will be seen that the arrangement of the terminal blocks 4 and 6 lends itself with great facility to the shielding of the high tension electrodes and cables in 60 order to prevent radiation therefrom which might interfere with radio signals. As there illustrated, the terminal block 4 is enclosed in a metallic shield 131 which is longitudinally split into two parts, a body portion 132 having an in-turned flange 133 adapted to fit beneath the edge of the block 4 and to be held by said block firmly grounded against the frame 1, and a cap 134 adapted to fit over the block 4 and to be secured to the body portion 132 by suitable means such as 70 screws 135 passing through flanges 136 and 137 formed on said parts.

Registering depressions 138 and 139 are provided in one end of the parts of the shield 131 forming, when the shield is assembled, a circu- 75

lar opening adapted to receive the end of a metallic sheath 141 for the cables 97. The sheath 141 is preferably provided with a terminal flange 142 which is adapted to bear against the inner sides of the parts of the shield 131 surrounding the opening 138, 139 and prevent withdrawal of the sheath from said opening.

It will be understood that the cables 97 are arranged to traverse the sheath 141 and such branches thereof as are necessary in order to completely shield the high tension circuit up to and including the spark plugs in the engine.

It will be noted that the blocks 4 and 6 may be readily removed from the frame 1 and applied thereto without the necessity of disassembling the shields or disconnecting the cables 97.

Attention is especially called to the advantageous arrangement of the various units upon the frame 1 whereby each unit is separately removable without disturbing any other unit and whereby the removal of the cap 113 allows direct access to the breaker mechanism for observation and adjustment without the necessity of removing or disconnecting any of the operating parts. It is thus possible to observe and adjust the breaker mechanism when the engine is in operation.

The advantages of the arrangement of the coil units and breaker mechanism and the driving means therefor as above set forth may be obtained in a replacement unit for a dual ignition system having separate distributors. Such a device is illustrated in Figs. 13 and 14 in which the parts of the frame, coil units, etc. are similar to those previously illustrated and are similarly numbered. The breaker mechanism has not been illustrated in this figure for the sake of clarity but it is to be understood that this mechanism in this embodiment of the invention is the same as that previously described. Since this device is to be used in conjunction with separate distributors, however, the distributor mechanism on the rotor shaft 8 is omitted, and a sleeve 142 placed thereon for the purpose of spacing the bearings 39 and 77 on said shaft. A pair of high tension cable connectors 143 and 144 are mounted in a block 145 of insulating material which is adapted to be mounted upon and to close one side of the frame 1 as by means of screws 146. The connectors 143 and 144 have conductors 147 and 148 which extend within the frame 1 and are provided at their inner ends with suitable connecting means such as spring brushes 149 and 151 which are arranged to make contact with the elements 36 of the transformer coils 13 and 14. The opposite side of the frame 1 is closed by a suitable plate 152 retained thereon by means such as screws 153.

The operation of this device is similar to that previously described except that the cables from the connectors 143 and 144 are led to the separate distributor devices, not shown, of the installation of which this device forms a replacement for the breaker and transformer mechanism.

Although certain forms, dimensions and arrangements of the parts have been shown and described in detail, it will be understood that various changes may be made in such particulars, and certain features thereof used without other features, and other embodiments of the invention will suggest themselves to those skilled in this art without departing from the spirit of the invention as defined in the claims appended hereto.

What is claimed is:

1. A distributor mechanism for dual ignition systems of internal combustion engines including a rotor having a plurality of conductors in axially offset relation, a plurality of sets of output electrodes arranged to cooperate in sequence with said conductors, a plurality of sources of high tension current, and commutating means on said rotor for connecting each of said conductors to each of said sources of high tension current in sequence.

2. A distributor mechanism for dual ignition systems of internal combustion engines including a rotor having a plurality of conductors in axially offset relation, a plurality of sets of output electrodes arranged in correspondingly offset relation to cooperate with said conductors and means for connecting said conductors in sequence to a source of high tension current whereby said source is connected first to the output electrodes of one set and then to those of another set.

3. In an ignition apparatus for internal combustion engines including a plurality of low tension and of high tension circuits, breaker mechanism for controlling said low tension circuits, a rotor having means on one end for operating the breaker mechanism, stationary high tension terminals arranged adjacent an intermediate portion of said rotor, a series of stationary output electrodes also arranged adjacent said intermediate portion, said intermediate portion having means for periodically conducting a discharge from said high tension terminals to each of said output electrodes.

4. A breaker-distributor mechanism for internal combustion engines including a substantially rectangular hollow frame, a breaker device movably mounted on one end of said frame, a plurality of high tension transformers removably mounted on the sides of said frame and having their primaries connected to said breaker device, said connections being automatically made and broken by the mounting and dismounting of the transformers and the breaker device on said frame.

5. A breaker-distributor mechanism for internal combustion engines including a substantially rectangular hollow frame, a breaker device movably mounted on one end of said frame, a plurality of high tension transformers removably mounted on the sides of said frame and having their primaries connected to said breaker device, a plurality of output electrodes removably mounted on the sides of said frame, means mounted in the frame for periodically connecting the high tension terminals of said coils to said output electrodes, the high tension connections being automatically made and broken by the mounting and dismounting of the transformers and of the high tension electrodes on said frame.

6. A breaker-distributor mechanism for internal combustion engines including a substantially rectangular hollow frame, a breaker device movably mounted on one end of said frame, a plurality of high tension transformers removably mounted on the sides of said frame, a rotor in said frame having cam means for operating said breaker device and having a distributor for periodically connecting the high tension terminals of the transformers to said output electrodes, both said transformer connections being automatically made and broken by the

mounting and dismounting of the transformers on said frame.

7. In an ignition device for internal combustion engines, a skeleton frame, a cap arranged to close one side of said frame, a transformer coil mounted as a unit in said cap and having a high tension element exposed toward the interior of said frame, a block arranged to close another side of said frame, output electrodes

10 rigidly mounted in said block extending toward the interior of said frame, and a rotary distributor in said frame having conductors arranged to periodically connect said high tension terminal with each of said electrodes.

15 8. In an ignition device for internal combustion engines, a skeleton frame, a plurality of caps arranged to be detachably mounted on opposite sides of said frame, a transformer coil mounted as a unit in each cap and having a high tension terminal exposed toward the interior of said frame, a plurality of blocks detachably mounted on said frame in alternation with said caps and having sets of output electrodes forming a plurality of circular series 20 thereof within said frame, and a rotary distributor within said frame arranged to periodically connect each high tension terminal with certain sets of said output electrodes.

25 9. In an ignition system for an internal combustion engine, a skeleton frame, a breaker device adapted to be mounted in the end of said frame, a cap arranged to close a side of said frame, and a transformer coil mounted as a unit in said cap, said breaker device and said transformer coil having conductors which are arranged to project within said frame and make electrical connection with each other when the breaker device and the cap are placed in position on the frame.

30 10. In an ignition device for internal combustion engines, a skeleton frame, an output device mounted therein, a breaker device adapted to be mounted in the end of said frame, a cap arranged to close a side of said frame and a transformer coil mounted as a unit in said cap, said transformer coil having conductors arranged to project within said frame, and said output device and breaker device having conductors adapted to make electrical connection with the corresponding conductors of the transformer coil when the cap and the breaker device are placed in position on the frame.

35 11. In an ignition device for internal combustion engines, a metallic skeleton frame, an insulating block arranged to close a side of said frame, output electrodes in said block, and a metallic shield for the exposed parts of said block remov-

able as a unit with said block and adapted to be grounded to said frame when the block is mounted therein, said shield having an opening for a cable sheath on one side and being split in the plane of said opening.

40 12. In an ignition device for internal combustion engines, a metallic skeleton frame, an insulating block arranged to close a side of said frame, output electrodes in said block, and a metallic shield for the exposed parts of said block removable as a unit with said block and adapted to be grounded to said frame when the block is mounted therein, said shield having an opening for a cable sheath on one side and being split in the plane of said opening into a body portion and a cap portion, said body portion being so formed as to be held by said block against said frame, and the cap portion being separately removable.

45 13. In an ignition device for internal combustion engines, a metallic skeleton frame, an insulating block arranged to close a side of said frame, output electrodes in said block, insulated cables anchored to said electrodes in said block, and a metallic shield for the exposed parts of said block, removable as a unit with said block, said shield having an opening on one side and being split in the plane of said opening to form a body portion and a removable cap portion, and a metallic sheath for said cables adapted to enter said opening and to be locked therein when the cap and body portions of the shield are in assembled relation.

50 14. A distributor mechanism for dual ignition systems of internal combustion engines including a rotor having a plurality of circumferentially spaced conductors, a plurality of axially spaced sets of output electrodes circumferentially spaced about said rotor and arranged to cooperate with said conductors, sources of high tension current, and commutating means on said rotor for connecting each of said conductors in sequence to each of said sources of high tension current.

55 15. In an ignition apparatus for internal combustion engines including low and high tension circuits, breaker mechanism for controlling said low tension circuit, a rotor driven at one end and having means at the free end for operating the breaker mechanism, sources of high tension current, high tension terminals connected thereto, and a circumferentially arranged set of output electrodes adjacent an intermediate portion of said rotor, said intermediate portion having a conductor for periodically completing a high tension circuit through each said high tension terminal and each of said output electrodes.

WALTER J. SPENGLER.
